FÜR DRAHTLOSE TELEGRAPHIE M. B. H., HALLESCHES, OF BERLIN, GERMANY, A
CORPORATION OF GERMANY.

CIRCUIT ARRANGEMENT FOR RECEIVING RADIOENERGY.

Application filed August 3, 1922. Serial No. 579,385.

To all whom it may concern:

Be it known that EMIL MAYER and AUGUST LEIB, citizens of the Republic of Germany, and residents of Hallesches Ufer 5 12/13, Berlin, S. W. 11, Germany, have invented new and useful Improvements in Circuit Arrangements for Receiving Radioenergy (for which we have filed application in Germany Aug. 2, 1921), of 10 10 which the following is a specification accompanied by drawings.

In all secondary receivers, it is necessary to tune first the primary circuit and then the secondary circuit to the unknown sender 15 15 by suitably varying the coupling of the two circuits. The present invention relates particularly to secondary receivers with cathode tubes and simplifies the tuning operation to a great extent. It has the further 20 20 advantage that no switching of the cathode tubes is necessary and that during the final transfer to the secondary receiver, the primary cathode tube has the new and important function of reducing the damping in the 25 25 primary circuit without any change in its connection with the primary circuit.

The single figure of the drawing is a diagrammatic representation of a simple circuit arrangement embodying the invention. 30

In accordance with the invention, the receiving arrangement consists of two tuned circuits, one of which I serves as a primary and the other II as a secondary circuit. 35 35 The circuits contain cathode receiving tubes RP and RS respectively, which are variably back coupled. During the primary receiving the telephone or other suitable indicator T and the primary receiving tube RP are 40 40 employed, and during the secondary receiving the cathode tube RS is used. In changing from primary to secondary receiving with the present arrangement, in which the cathode tube RP of the primary receiving 45 45 circuit is not switched off but is permitted to continue in operation, the primary cathode tube RP may be caused not to produce oscillations and the resistance of the primary circuit I and, consequently, the damping 50 50 of the received energy may be materially reduced by suitably adjusting the back coupling R of the tube RP to the primary circuit. In the use of the invention, the primary receiver not only enables the arrange-

ment to be tuned readily to the wave length 55 of the incoming energy and thereby facilitates the tuning of the secondary receiver, but the continued operation of the primary receiver during receiving through the secondary receiver reduces the damping in the 60 primary circuit and thus improves the action of the secondary receiver. The secondary tube RS is differently back coupled to the secondary circuit, depending upon whether it is used for producing local oscillations, 65 or as a simple audion when there is a separate transformer. The use of the primary tube RP for the purpose of back coupling and reducing the damping makes possible the employment in all circuits of high resistance 70 coils wound with thin wire. Such coils are cheap and consume only slight current, and the action of the tube RP in reducing the damping enables coils of such character to be used without detracting from the selectivity of the arrangement. 75

In accordance with the present invention, one may go even further and provide a similar third circuit which also comprises a cathode tube with variable back coupling 80 whereby a tertiary receiver is obtained with damping reduction in all circuits, or the third circuit may be used as a wave meter. The variable back coupling makes it possible to use the cathode tube in this circuit 85 as a simple detector, and in this manner the wave meter may be used as a receiver or, by using a second calibration scale, the back coupling may be made closer so that the tube operates as a generator and the sender becomes a sending wave meter. In this case 90 the tuning in the circuit to be tuned is tested by means of the telephone.

Having described our invention, what we claim is:

1. A circuit arrangement for receiving radio energy, comprising a primary tuned circuit, a secondary tuned circuit coupled with the primary circuit, and a plurality of thermionic vacuum tubes one of which is 100 connected on its input side to the secondary tuned circuit and is back-coupled to said secondary circuit so as to be operable to produce oscillations therein and to act as a detector and the other of which is connected on its 105 input side to and back-coupled with the primary circuit, thereby causing it to be operable at will either as a detector, when the

first mentioned tube is used as an oscillator, or to reduce the apparent resistance of the primary circuit for the frequency being received, when the first-mentioned tube is operated as a detector, and thereby reduce the damping of the received energy.

2. A circuit arrangement for receiving radio energy comprising a primary tuned circuit, a secondary tuned circuit coupled with the primary circuit, a primary receiver and a secondary receiver, said secondary receiver comprising a thermionic vacuum tube connected on its input side to said secondary circuit and back-coupled thereto so as to be operable to produce oscillations and as a detector and said primary receiver comprising a thermionic vacuum tube connected to the primary circuit and back-coupled thereto, said back-coupling being adjustable so as either to cause the primary vacuum tube to act as a detector or to reduce the apparent resistance of the primary circuit and, consequently, the damping of the received energy which is supplied to the secondary receiver.

3. A circuit arrangement for receiving radio energy comprising a primary tuned circuit, a secondary tuned circuit coupled with the primary circuit, a primary receiver and a secondary receiver, said primary receiver comprising a thermionic vacuum

tube and an indicator and being adjustably back-coupled with the primary circuit, and said secondary receiver also comprising a thermionic vacuum tube and an indicator and being adjustably back-coupled to the secondary circuit.

4. A circuit arrangement for receiving radio energy comprising a primary tuned circuit, a secondary tuned circuit, coils for coupling said circuits together, a primary receiver and a secondary receiver, said secondary receiver comprising a thermionic vacuum tube connected on its input side to said secondary circuit and coils for back-coupling the output side of the vacuum tube to said secondary circuit so as to cause the tube to be operable to produce oscillations and as a detector, and said primary receiver comprising a thermionic vacuum tube connected to the primary circuit and coils for back-coupling the output side of the primary tube to the primary circuit, said coils being of small size and being wound with thin wire having high resistance and said last-mentioned coils being adjustable so as either to cause the primary vacuum tube to act as a detector or to reduce the apparent resistance of the primary circuit, and, consequently, the damping of the received energy.

EMIL MAYER.
AUGUST LEIB.
